UNITED STATES PATENT OFFICE.

WALTER L. DIXON, OF BOSTON, MASSACHUSETTS, ASSIGNOR TO REECE FOLDING MACHINE COMPANY, OF BOSTON, MASSACHUSETTS, A CORPORATION OF MAINE.

FOLDING MACHINE.

Application filed August 21, 1924. Serial No. 733,298.

This invention involves a novel folding machine, that is, an apparatus for infolding the edges of cloth or other blanks, for example the cloth blanks used in the manufacture of collars and cuffs, and involves also a novel method of folding such blanks, more especially blanks of certain specific shapes, and involves also a novel product, that is to say a folded blank or a completed collar or other article embodying the particular and novel form of fold of this invention.

The general object of the invention is to afford an improved folding machine, method and product, of general and specific utility in the arts. A special object is to improve the art of folding cloth blanks for collars, cuffs, and other articles of clothing, etc. A particular object is to enable the efficient and satisfactory manufacture of collars or analogous articles wherein one or more of the corners to be folded is a fairly sharp angle, or an acute angle, substantially less than 90°. With the shapes having such a corner or corners there has been a problem in producing a satisfactory fold on account of the difficulty in accommodating the excess of marginal material within the small compass of the acute angle. With previous attempts these corners have been folded in a way to produce excessive thickness or even bunching of material, resulting in an unsightly and uncommercial product, and sometimes even requiring trimming off the excess material, necessarily a separate and manual operation, adding materially to the cost of manufacture. Other and further objects of the present invention will be explained in the hereinafter description of an embodiment thereof, or will be apparent to those skilled in the art.

To the attainment of the objects and advantages referred to the present invention consists in the novel machine or apparatus, and the novel method of operation or manufacture, and the novel infold or product, as well as the novel features of combination, arrangement, construction, mode of action and detail, herein illustrated or described.

In the accompanying drawings Fig. 1 is a top plan view of a folding machine embodying the present invention, the same being of the general type illustrated by the patents of Dixon 956,950 and Reece 972,916, although the features could be embodied in very different types. In Fig. 1 the defining

templet or die is omitted, the infolders are shown in their outward positions ready to be moved inwardly, and the blank is shown in position to be defined by the templet and infolded.

Fig. 2 is a top plan view of the templet and its mounting and operating connections.

Fig. 3 is a bottom plan view of the same.

Fig. 4 is a front elevation of the templet.

Fig. 5 is a right elevation thereof, with certain adjacent parts shown in section.

Figs. 6 to 9 are partial plan views on an enlarged scale showing successive stages in the process subsequent to the initial condition shown in Fig. 1.

Fig. 10 shows a part of the original infolded blank, corresponding to Fig. 1.

Fig. 11 shows the same in a partly folded condition, corresponding to Fig. 6.

Fig. 12 shows the completely folded blank, corresponding to Fig. 9.

For convenience the description may be begun with the method and product, and the apparatus described subsequently. It may be assumed that the present embodiment is adapted for the manufacture of a so-called collar top, that is, the outside portion of a collar, of an outline having a sharp angle, as stated. Usually in constructing such an article two folded blanks are prepared, assembled and stitched together, although sometimes a single infolded blank may be used as a collar top. In either case the present invention may be employed for the production of each infolded blank presenting a sharp angled corner. Each blank may consist of either one or more plies of cotton, linen, or other fabric or sheet material. It will be understood that the folds may be oppositely formed at the two ends of the article so that in assembling two blanks the folds may be tucked in under each other, forming what is known as a lock corner.

In one aspect, the present method may be described as comprising first defining the blank at the sharp corner with an obtuse angled outline, and thereupon partially infolding the fabric margins, followed by an adjustment to reduce the defined angle to that of the desired sharp corner, and finally completing the infolding. In this way the excess material at the corner is not left to haphazard arrangement but is preliminarily formed into an orderly arrangement, the subsequent operation continuing the orderly

60

70

80

90

95

100

105

110

arrangement, so that the infold is accurately formed of the desired outline, with the excess material snugly encompassed flatly within the angle. Stated another way, the 5 lineal margins of the blank are folded in but the excess margin material at the corner being first arranged and laid down flatly before completing the operation. One lineal margin of the blank is infolded and the corner 10 material formed into a flap or flaps, which are then laid down upon the first fold, and the second lineal margin then folded in, completing the operation. The product is 15 characterized by having the inturned lineal margins which meet at the corner, and one or more neatly infolded flaps or loops of material located beneath the final infold and consisting of the original corner margin material.

20 The original, sharp cornered fabric blank 20 is indicated partially in Fig. 1 and Figs. 6 to 12, showing the sharp angled corner at one end of the blank. It will be understood that the other end of the blank may be substantially 25 symmetrical, and the entire blank of various contours, for example as indicated by the bottom view of the defining templet in Fig. 3.

Fig. 10 shows a portion of the blank 20 30 detached from the machine, and this figure indicates the eventual lines of side fold 21 and end fold 22, the intersection of these constituting the sharp or acute angle mentioned. Outside of the fold line 21 is the 35 fabric side margin 23, and outside the end fold line 22 is the margin 24. Beyond the corner or apex is the corner marginal material 25 which is required to be properly handled to produce a satisfactory final result.

40 Figs. 1 and 10 show the blank in its original condition. Figs. 6 and 11 show the blank at a preliminary stage of the infolding operation. Figs. 7 and 8 show the following stages, and Figs. 9 and 12 the final stage. 45 The plan of this invention is preliminarily to define two edges presenting an obtuse angle at the corner in question, for example by the aid of a temporary defining element, and to infold the blank over such defined edges, 50 afterwards reducing the angle to that desired and completing the infolding. The preliminary or temporary line of defined fold may be as indicated at 26 in Fig. 10. In Figs. 6 and 10, therefore, the blank is defined along the lines 21 and 26, and in this 55 condition the infolding means operate to turn in the blank margins over both of such defined edges. The margin material 23 is thus formed into an infold 23^a, as seen in Fig. 11, while the corner material 25 forms 60 itself into an upstanding flap 25^a. This operation is preferably done by an infolder having edges corresponding substantially with the lines 21 and 26, and the infolding 65 movement is preferably at once continued so

as to turn inwardly and down upon the infold 23^a the upstanding flap 25^a, as sufficiently indicated in Fig. 7. This stage being completed the obtuse angled definition is next discontinued and the angle reduced to 70 the desired sharp angle, for example by the removal of the temporary defining element mentioned. This leaves the end margin 24, with its partially infolded corner, in condition to be infolded upon the folds already 75 formed, as seen in Fig. 8; and this is preferably done by a separate infolding edge, approaching from the end, turning in and laying down the end margin 24 in the form of an infold 24^a, as indicated in Figs. 9 and 80 12. By proper designing of the parts the intermediate flap or fold 25^a may be wholly enclosed and concealed by the end margin 24^a, as indicated.

Referring to the illustrated machine, this 85 is shown as comprising a supporting bed or pad 30 on which the unfolded blanks are laid. The bed may be heated, as usual, and is shown as scored in part to minimize slippage of the fabric. The bed is preferably 90 stationary but may have lifting movements to give squeezing pressure upon the infolded blanks in a well-known manner. The bed is supported by a frame, portions 31 of which are indicated, which may be similar 95 to the prior patents. A power shaft 32 may operate through a worm wheel 33 to give slow rotation to the main shaft 34 on which the cams are carried. Supported out at the rear is shown a shaft 35 by which the 100 templet may be swung for its up and down movements. A gear 36 loose on the shaft 35 is shown in mesh with an intermediate gear 37 engaging a gear 38 on the cam shaft 34, thereby transmitting rotation to the cam 105 mechanism of the templet. The gear 36 is secured to a sleeve 39 loose on the shaft 35 and carrying the cams to be described. Extending forwardly from the fulcrum shaft 35 are two templet carrying arms 40, 110 at the forward ends of which is supported a frame 41 carrying the movable parts of the templet. The carrying arms 40 may be secured to the fulcrum shaft and the templet may be raised and lowered through any system of levers or the like, as indicated in prior machines or applications. For example, a rearward arm 42 may be connected by a bell crank lever with a cam on the main 115 shaft.

120 The defining portion of the templet may consist of a plurality of thin defining plates, and these may be contracted so as to extract them from the folds and permit effective creasing between the bed and infolders. 125 For example, the templet may consist of two end plates 43 each having an end edge 44 and a side edge 45, and a middle templet plate 46 bridging over the space between the two end plates. A convenient manner 130

of movement for the templet plates is to have all of them moved bodily toward the front side of the machine while the end plates approach each other, thus effectively extracting the templet from the rear side and two end folds of the blank. Such movement is enabled by the following mechanism.

A body member 47 is shown directly carrying the middle templet plate 46. It is constructed in the form of a longitudinal bar, capable of shifting forwardly and rearwardly. Rods 48 carry the body member 47, and said rods are guided in the templet frame 41. The rear ends of the rods are connected by a cross bar 49, the middle part of which is supported by a guide rod 50. These parts are moved bodily forward through a cam yoke 51 connected to the bar 49 and straddling the sleeve 39 on shaft 35, the yoke having a cam pin engaging a cam 52, mounted on sleeve 39, all substantially as in machines heretofore known.

For causing shortening movements of the end plates 43 of the templet are shown a pair of cams 54 on sleeve 39 cooperating with yokes 55, each of which reciprocates a cam plate 56 having a cam slot 57 engaging a pin 58 upstanding from endwise moving supporting blocks 59 which carry the defining plates 43. The cam slots 57 have eccentric portions such that the bodily forward movement of the templet causes simultaneous shortening thereof, and the cam slots also have dwells, so that, as controlled by the cams 54, any desired contracting movements may be effected. The templet plates 43 may be adjustably carried beneath the supporting blocks 59 through slides 60 guided on the blocks and directly carrying the plates, so as to permit adjustment for varying lengths of blank to be folded. No special novelty is herein claimed in relation to the details just described.

The means for preliminarily enlarging the subtended angle defined at the corner of the blank is preferably an extra or supplemental defining element or edge, shown in the form of a small angular plate 65 adapted to be removably positioned upon the margin of the blank adjacent to the corner of the templet and outside of one edge of the templet. This additional defining piece may be mounted in various ways and operated by hand or automatically. It may be mounted upon the bed or infolders and independent of the templet; but preferably is mounted on the same rising and falling frame which carries the templet.

In the specific form illustrated the supplemental defining piece 65 has an edge 66, adapted to lie adjacent to the end edge 44 of the templet, and an edge 67 adapted to form an obtuse angle with the edge 45 of the templet. It will be understood that the

templet edge 45 and the defining piece edge 67 correspond with the fold lines 21 and 26, respectively, in Figs. 10 and 11. The requirement as to operation of the defining piece 65 is that it shall be positioned as 70 stated during the first part of the folding, so that the blank is partly folded with an obtuse angle, and that it shall then be removable or withdrawn to permit the completion 75 of the folding, a portion of the obtuse angle being turned over upon the templet edge 44, thus giving a neat and satisfactory infolded blank.

An advantageous arrangement is to construct the defining piece 65 of thin metal, so properly sharpened, extending forwardly from the defining position and then upturned at 68 and bent again forwardly at 69, with the forward end properly secured to a suitable support. This construction 85 gives resilience so that when the piece 65 is retracted from the temporary fold it may readily yield upwardly during the final infolding operation, thus avoiding conflict with the infolders. Preferably the removal 90 of the defining piece from the partly folded blank is automatic, and for this purpose the horizontal holding portion 69 is mounted upon a shiftable carrier 70. This carrier is shown as a rigid L-shaped member ful- 95 crumed at its inner end 71 so that its outer end can swing forwardly for the retracting movement and subsequently return to re-position the defining piece. The pivots 71 are mounted on the longitudinally adjust- 100 able slides 60, permitting the defining pieces to be adjusted when the templet is altered in length. When the templet length is changed this simultaneously shifts the defining pieces to correspond. For adjusting 105 the defining piece accurately to the templet plate a screw stop 72 is shown giving rearward adjustment, and the plate may be adjustable endwise for a similar purpose.

These forward and rearward movements 110 of the carrier 70 may be effected positively through pins 73 upstanding from each carrier, the upper ends of the pins engaging with a longitudinal actuator bar 74, which has a groove 75 to receive the pins, thus 115 permitting the adjustment of the parts for blanks of different lengths. The central part of the bar 74 is secured at the forward end of a sliding plate 76 which is mounted slidingly in the templet frame 41 and at 120 its rear end is provided with a yoke 77 surrounding the fulcrum sleeve 39 and having a cam pin 78 engaging a cam 79, the contour of which is indicated in Fig. 5. This contour and that of the other cams 125 need no specific description further than the statement of operation to be hereinafter set forth.

The folding means may take various forms but I prefer thin, metallic infolder 130

plates moved inwardly and outwardly and preferably raised and lowered during operation. Side edge infolder plates 84 and 85 are shown arranged along the rear side of the infolding position, and at the left end, not seen in Fig. 1, may be a symmetrical plate similar to 85.

The infolder plate 85 is preferably specially constructed to cooperate in the particular purpose of the present invention. It is shown as having a longitudinal folding edge 86 and, near the corner, an inwardly inclined edge 87 forming an obtuse angle with 86; these two edges corresponding with the defining edges 45 and 67 and with the folding lines 21 and 26. These edges 86 and 87 take part in the preliminary folding. Preferably a slight notch 88 is formed at their junction. The infolder 85 also preferably has an exterior edge 89 adapted momentarily to define the end edge in the second stage of operation, or at least to hold the fabric in place when the end folder rises and starts inward.

25. The infolder 85 may be mounted on a heavier stock or body 90. Attached to this stock and at other convenient points may be gages 91 to assist the initial positioning of the blank. The rear side infolders 84 and 85 may be moved inwardly and outwardly by a bar 92, actuated by connections not shown, from a cam 93, or a plurality of such cams. The actuator bar 92 has longitudinal slots 94, one of which serves to guide a portion of the stock 90, thus permitting the infolder 85 to be moved longitudinally, the stock being held in the slot by an overlying plate 95. The middle infolder 84 may be permanently secured in one of the slots 94 of the bar 92.

For the purpose of giving the infolder 85 suitable endwise movements the stock 90 is shown extended to the right at 96 in Fig. 1, its extremity having a cross slot 97 receiving a pin 98 mounted on a push rod 99 the outer end of which is adjustably secured upon a block 100 at the upper end of a cam lever 101 fulcrumed at its lower end and having a pin 102 extending into the groove 50 of a cam 103. The cams 93 and 103 work in cooperation to give the infolder 85 its required movements. A cam 104 is shown arranged to control the upward and downward movements of the rear side infolders, 55 as already mentioned.

The end infolder 110 may be arranged to have a simple endwise movement through suitable guiding means. A recessed block 111 on top of the end infolder is engaged by a pin on a push rod 112 similar to the push rod 99. The outer end of the push rod 112 is adjustably mounted on a block 113 formed at the top of a cam lever 114 having a pin or follower 115 engaging a cam 116, 60 this cam giving full control of the in and

out movements of the end infolder. A cam 118 lifts and lowers the infolder 110, which initially lies flush with the bed and below the operating level of the side infolder 85.

The operation may be substantially as follows. Fig. 1 shows the unfolded blank 20 of Fig. 10 laid in position against the gages 91 and on top of the bed and infolder edges. The templet descends toward the bed and comes down upon the blank, causing its side 75 margin 23 to be turned up against the side infolder 85, the notch 88 commencing to form the fabric into a loop. The defining piece 65 comes down with the templet. The side infolder 85 now starts inward in a forward direction, but at once changes to diagonal inward movement. The forward movement forms the loop 25^a as seen in Figs. 6 and 11, and the diagonal movement lays the loop over as in Fig. 7. The defining 80 piece 65 up to now has been in position as in Figs. 1, 3, 6 and 7, but is now withdrawn by its cam 78, to the position seen in Fig. 8. Preferably the side infolder now continues in a longitudinal direction, until reaching 85 Fig. 8 position, with the infolder edge 89 approximately coinciding with the end edge of the contour. At this time the end infolder 110 lifts, thus turning up the fabric, and the defining piece yielding upwardly, 90 and the folder then starts longitudinally inward, laying the blank margin 24 over and down. During this movement the side infolder preferably moves inward slightly in advance of the end infolder, and with a 100 diagonal movement, giving an ironing action on the material as it is laid over and down. The conditions at this stage are indicated by Figs. 9 and 12. The folding is done. The templet may be contracted out of the folds 105 and lifted, the folds squeezed between bed and infolders, and the infolders retracted, leaving the blank as in Fig. 12, ready to be removed to give place to a new one. The infolders preferably are retracted slightly 110 beyond their initial position, and moved forward to the initial position as in Fig. 1, and brought to rest there in readiness to start a new cycle of operations.

It will thus be seen that there has been 115 described a folding machine or apparatus, a folding method, and a folded blank or collar, embodying the principles and attaining the advantages of the present invention. Since many matters of arrangement, combination, structure, operation and detail may be variously modified without departing from the principles of the invention, it is not intended to limit the same to such matters except in so far as set forth in the appended claims.

What is claimed is:

1. A machine for infolding collar blanks or the like having adjacent edges meeting at a sharp corner comprising obtuse angled 130

means for first interiorly defining the blank at the sharp corner with an obtuse angled outline, and for subsequently changing the interior defining means to reduce the defined angle to the desired sharp angle, infolders 5 for the edges meeting at such corner, and means for actuating the infolders first to infold over both edges of the obtuse angled defining means, and after the reduction of 10 angle to infold to the sharp angle.

2. In a machine for infolding collar blanks and the like presenting an outline having adjacent edges meeting at a sharp angled corner, a support for a blank, defining mechanism for first subtending an enlarged angle at said corner and having 15 means for reducing the angle to the desired sharp angle, infolders, and means for actuating the infolders to fold blank edges partially over the enlarged angle defining 20 mechanism and to complete the infolding after the reduction of the angle.

3. A machine for infolding collar blanks or the like having adjacent lineal edges meeting at a sharp corner consisting in means for 25 first defining one of such lineal edges and an edge at obtuse angle thereto, and subsequently both of such lineal edges, infolders, 30 means for actuating said infolders first to infold the blank over both such first defined edges, and subsequently to infold the blank over the other lineal edge.

4. In a machine for infolding collar blanks or the like, a support for a blank to 35 be infolded, a templet defining the two edges meeting at a given corner, an extra defining piece adapted to be removably positioned upon the margin of the blank adjacent to such corner outside one templet edge to enlarge 40 the subtended angle, means for infolding blank margins at both sides of such angle over the templet and defining piece, means for withdrawing the defining piece, means for infolding the remaining blank 45 margin over the corresponding templet edge, and timed mechanism operating said defining piece and infolding means in the order stated.

5. In a machine for infolding collar 50 blanks or the like, a support for a blank to be folded, a templet fitted to be positioned upon the blank and adapted to define the two edges meeting at a sharp corner, a defining member adapted to be removably positioned 55 upon the blank margin adjacent to such sharp corner for enlarging the subtended angle to an obtuse angle, infolders, means for operating the infolders first to infold the blank margins at both edges of 60 the obtuse angle and form the excess material into a loop, and subsequently, after the withdrawal of the defining member, to infold the material vacated by said member, and means for withdrawing the defining member during the infolding operations.

6. Infolding machine as in claim 5 and wherein is means for positioning the templet and defining member upon the blank in the same operation, whereas the means for withdrawing the defining member is operable 70 independently of the templet.

7. Infolding machine as in claim 5 and wherein the defining member is composed of resilient metal capable of yielding during 75 the final infolder action.

8. Infolding machine as in claim 5 and wherein the defining member is pivotally mounted on the supporting parts of the templet, with means to swing the same for its withdrawal.

9. Infolding machine as in claim 5 and wherein the defining member is a plate mounted on a swinging carrier, and automatic means to swing the carrier.

10. Infolding machine as in claim 5 and wherein the templet comprises movable plates, a frame supporting the plates a fulcrum about which the frame swings, and a cam rotating about the axis of templet swinging for effecting the withdrawal of the 90 defining member prior to the contraction of the templet plates.

11. Infolding machine as in claim 5 and wherein one of the infolders comprises a re-entrant obtuse angle operating both at one 95 templet edge and the edge of the defining member.

12. Infolding machine as in claim 5 and wherein one of the infolders comprises a re-entrant obtuse angle operating both at one 100 templet edge and the edge of the defining member, said infolder having an external edge (89) adapted to define the final fold, and an infolder adapted to form the final fold.

13. Infolding machine as in claim 5 and wherein one of the infolders comprises a re-entrant obtuse angle operating both at one 110 templet edge and the edge of the defining member, with a notch at the apex assisting forming the material into a loop or flap.

14. Infolding machine as in claim 5 and wherein the infolders comprise an infolder operating at both sides of the obtuse angle and moved inwardly to fold both margins 115 and lay the intermediate loop down within the sharp angle subtended by the templet, and a second infolder operating after the defining member is withdrawn and moved inward in cooperation with the first infolder 120 to lay the final fold smoothly in place.

15. In a machine for infolding collar blanks or the like, a support for a blank to be folded, a templet fitted to be positioned upon the blank and adapted to define the two edges meeting at a sharp corner, a defining plate adapted to be removably positioned upon the blank margin adjacent to such sharp corner for enlarging the subtended angle to an obtuse angle, infolders, means for 130

operating the infolders first to infold the blank margins over the templet and plate at both sides of the obtuse angle and form the excess material into a loop and lay the same

5 down within the angle subtended by the templet, and subsequently, after the withdrawal of the defining plate, to infold the

material vacated by said plate, and means for withdrawing the defining plate from the infolded material after the first and before 10 the last infolding operation.

In testimony whereof, I have affixed my signature hereto.

WALTER L. DIXON.
